UNITED STATES PATENT OFFICE.

HOWARD L. PYLE, OF WILMINGTON, DELAWARE.

HEATER-BOX.

1,168,742.

Specification of Letters Patent.

Patented Jan. 18, 1916.

Application filed February 21, 1912. Serial No. 679,100.

To all whom it may concern:

Be it known that I, HOWARD L. PYLE, a citizen of the United States, residing at Wilmington, in the county of New Castle, State of Delaware, have invented new and useful Heater-Boxes, of which the following is a specification.

My invention relates to a new and useful heater box for use in a fire box, whereby I am enabled to direct a suitable quantity or amount of heated air into the fire box above the body of the fuel in order to cause a complete combustion of the products of combustion and to assist in the combustion of the fuel.

It further consists in providing means for injecting steam into the heater box and controlling the steam supply.

It further consists in providing additional heating or radiating surfaces within the heater box, and in varying the direction of flow through the heater box.

It further consists of other novel features of construction all as will be hereinafter fully set forth.

The annexed drawings and the following description set forth in detail one mechanical form embodying the invention, such detail construction being but one of various mechanical forms in which the principle of the invention may be used.

Figure 1 represents a sectional view on line $x-x$, Fig. 2. Fig. 2 represents a sectional view on line $y-y$, Fig. 1. Fig. 3 represents a sectional view on line $z-z$, Fig. 2. Fig. 4 represents on an enlarged scale a sectional view of the socket for operation of the device in detached position. Fig. 5 represents on an enlarged scale a perspective view of the nozzle employed. Fig. 6, represents an elevation on an enlarged scale of a form of heater box which may be employed. Fig. 7 represents a top body plan view of the heater box.

Similar numerals of reference indicate corresponding parts in the figures.

Referring to the drawings: It will be understood that my heater box is applicable to be used in any suitable form of a fire box, and, as here shown and described, I have provided the same to the fire box of a locomotive which may be of any suitable or desired type.

1 designates the boiler casing having a suitable fire box 2, provided with the grate bars 3 and with the water tubes 4. At a

suitable point in the fire box, preferably in the corners adjacent the fuel supply opening 5, I mount the heater boxes 6 which are preferably supported in any suitable manner upon the grate bars 3. As here shown, I provide the sleeve 7, suitably supported and having the extension 8 adapted to receive the lower end of a heater box 6, and also connected with the sleeve 7 is a pipe 9, provided with a collector 10, the opening of which is preferably provided with a screen 11, it being noted more particularly from Figs. 1 and 2 that the pipes 9 curve outwardly in order that the collectors are suitably positioned with respect to the boiler casing 1, and the direction in which the engine is moving, in order to collect the air and direct the same into the heater boxes 6. The upper end of the heater boxes is preferably provided with a nozzle 12 provided with a suitable shaped outlet or discharge opening 13 and so positioned as to direct the air therefrom forwardly and across the fire box, as best understood from Fig. 1, so that the air from the respective nozzles will cross at a suitable point above the fuel in order to thoroughly commingle with the products of combustion, so that the same will be consumed, it being further noted that the direction of travel of the air from the nozzles is in the same natural course and is in the same substantial direction as in the natural flow of the products of combustion, in order to provide that the air passing into the nozzles 12 will be suitably heated. I preferably desire to provide upon the interior of the heater a series or a plurality of extensions or baffles against which the air impinges in order that the same will be thoroughly heated to the proper temperature.

In the construction shown in Figs. 6 and 7, I have shown the projections or extensions 16, as being suitably curved in order to provide a curved path through which the air passes, imparting a swirl thereto, and so that the air will be suitably heated. In this manner, it will be understood that I provide means whereby the air will be properly and thoroughly heated, before being discharged into the fire box, in order to provide a more perfect combustion than where the air would pass through the heater boxes which are not provided with the extensions 16 or projections. In some instances, I have found it desirable to provide means for in-

jecting steam into the heater boxes and to control the supply of steam thereto, so that the same can be regulated, or entirely cut off.

5 As here shown, I provide a pipe 17 connected with a suitable part of the boiler and having a controlling valve 18, which it will be understood, can be located at a suitable point in the cab for easy access of the engineer. The lower end of the pipe 17, is provided with the branches 19 and 20, one of which will discharge to the heater box, which is on one side of the fire box and the other of which will discharge into the heater 10 box 6 on the other side. By this means, it will be understood that by opening the valve 18 a suitable supply of steam can be injected into the heater box 6, which will assist in drawing in the air through the collectors, 15 and as the steam and air commingles, will be properly heated and discharged into the fire box to assist in the complete consumption of the products of combustion.

20 Having thus described my invention, what 25 I claim as new and desire to secure by Letters Patent, is:—

30 1. In a device of the character stated, a boiler, a fire box therefor, a suitable grate, a heater box in said fire box adapted to direct air thereinto and spiral flanges projecting from the inner wall of said heater box forming spiral passages and a central passageway with which the said spiral passages communicate throughout their entire extent.

35 2. In a device of the character stated, a boiler, a fire-box therefor, a suitable grate,

a heater box in said fire-box adapted to direct air thereinto, and spiral flanges projecting from the inner wall of said heater box forming spiral passages and a central passageway with which the said spiral passages communicate. 40

3. In a device of the character stated, a boiler, a fire-box therefor, a suitable grate, heater boxes in said fire-box adapted to direct air thereinto, spiral flanges projecting from the inner wall of each of said heater boxes forming spiral passages and a central passageway with which the said spiral passages communicate, and offset discharge portions for said heater boxes arranged to discharge air above the bed of fuel in the direction of the draft and so that the discharge therefrom will commingle with each other. 45

50 4. In a device of the character stated, a boiler, a fire-box therefor, a suitable grate, heater boxes in said fire-box adapted to direct air thereinto, spiral flanges projecting from the inner wall of each of said heater boxes forming spiral passages and a central 55 passageway with which the said spiral passages communicate, and offset discharge portions for said heater boxes arranged to discharge air above the bed of fuel in the direction of the draft, said discharge portions being flat and elongated, whereby the discharge therefrom is in sheet form and arranged to commingle with each other. 60
